(57) **CLAIM**

The ornamental design for an antrum punch forceps, as shown and described.

DESCRIPTION

FIG. 1 is a bottom left side isometric view of an antrum punch forceps in accordance with the new design;

FIG. 2 is a left side isometric view thereof;

FIG. 3 is a right side isometric view thereof;

FIG. 4 is a top isometric view thereof;

FIG. 5 is a bottom isometric view thereof;

FIG. 6 is an enlarged front isometric view thereof; and,

FIG. 7 is an enlarged rear isometric view thereof.

The broken lines shown in FIGS. 1, 2, 5, and 6 represent the bounds of the claimed design and form no part of the claimed design.

1 Claim, 7 Drawing Sheets

FIG. 2

FIG. 4

FIG. 5
